PIEZOELECTRIC TRANSDUCER

Walter L. Cherry, Jr., Northbrook, Ill., assignor
to Zenith Radio Corporation, a corporation of
Illinois

Application May 17, 1949, Serial No. 93,700

6 Claims. (Cl. 179—110)

1

This invention relates to piezo-electric transducers, and more particularly to such transducers as disclosed and claimed in the copending application of Walter L. Cherry, Jr., Serial No. 770,163, filed August 22, 1947, for "Piezo-Electric Transducers," now U. S. Patent 2,538,554 dated January 16, 1951, and that of Robert Adler, Serial No. 793,892, filed December 26, 1947, for "Piezo-Electric Transducers and Methods for Producing Same," now U. S. Patent 2,540,412 issued February 6, 1951, both of which applications are assigned to the same assignee as the present application.

The above-identified Cherry application discloses and claims a process for producing a piezo-electric effect in a polycrystalline aggregate comprising barium titanate or barium strontium titanate. Briefly, the process comprises subjecting the aggregate to a unidirectional electric polarizing field and maintaining the field until saturation of the piezo-electric effect. Upon removal of the field thereafter, the aggregate retains a remanent piezo-electric effect of substantial magnitude.

The above-identified Adler application broadly discloses and claims a piezo-electric polycrystalline aggregate transducer in which the direction of the piezo-electric axis varies at a non-uniform rate from portion to portion. As a preferred embodiment, the application discloses a piezo-electric polycrystalline aggregate transducer in longitudinally adjacent portions of which the direction of the piezo-electric axis is substantially opposite. Such a transducer may be produced by a process of reverse alternate polarization, as disclosed in the Adler application, and is characterized by a substantially greater capacity than a simply polarized aggregate body of similar dimensions; at the same time, the electromechanical coupling coefficient of the transducer is maintained at the same order of magnitude of that of a simply polarized piece.

A particular embodiment shown and described in the Adler application comprises a bimorphic composite element including a pair of juxtaposed polycrystalline aggregate bodies having a plurality of spaced conductive strips or electrodes disposed on the outer surfaces of the element. In order to provide a pair of output terminals, alternate strips or electrodes are interconnected. In practice, the electrode structure assumes the appearance of a pair of inter-meshing combs, formed of conductive paint and fired onto the surfaces of the ceramic bodies. In order to utilize the electrical output obtained from a transducer of this sort, it is necessary to provide output leads respectively soldered or otherwise connected to

the conductive paint output terminals on the surfaces of the elements. It has been found that a transducer so constructed must be handled with extreme care to avoid rupturing the joint between the output leads and the conductive paint terminal strips.

It is therefore, an important object of the present invention to provide an improved bimorphic polycrystalline aggregate transducer of the type described above which does not require as extreme care in handling as do previous transducers of this type.

There is a further disadvantage inherent in the use of electrodes of the inter-meshing comb type. With such an arrangement, the individual electrodes extend to within a relatively short distance of the shorting strip constituting the opposite output terminal. Since the materials used are characterized by an extremely high dielectric constant, of the order of 1200 or more, the inter-meshing comb arrangement results in an undesirable shunt capacity between the output terminals and in an undesirable piezo-electric component in a transverse direction. Both of these undesirable effects act to reduce the useful output voltage. On the other hand, if a large distance is left between the individual strips and the opposite output terminal, so as to avoid the undesirable shunt capacity, a large portion of the aggregate remains unused for providing useful electrical output, and the efficiency of mechano-electrical conversion is low.

It is a further object of the invention, therefore, to provide an improved bimorphic piezo-electric polycrystalline aggregate transducer, of the reverse alternate polarization type, in which the mechano-electrical conversion efficiency is high, and at the same time, in which the previously encountered undesirable shunt capacity and transverse piezo-electric component effects are effectively minimized.

A piezo-electric transducer constructed in accordance with the present invention comprises a composite bimorphic element including a pair of juxtaposed polycrystalline aggregate bodies and having permanent piezo-electric properties with the direction of the piezo-electric axis different in adjacent portions in each of the bodies. Conductive strip terminals or electrodes are disposed between such adjacent portions on the outer surfaces of the composite element. A plurality of terminal leads are supported between the bodies and individually electrically connected with respective ones of the strip terminals, and a pair of conductors respectively connect alternate terminal leads to provide a pair of output terminals.

The features of the present invention which are

2

believed to be novel are set forth with particularity in the appended claims. The invention, together with further objects and advantages thereof, may best be understood, however, by reference to the following description taken in connection with the accompanying drawing, in the several figures of which like reference numerals indicate like elements, and in which:

Figure 1 is a plan view, partially cut away, of a hearing aid microphone constructed in accordance with the present invention.

Figure 2 is a sectional view taken along the line 2—2 of Figure 1.

Figure 3 is a perspective view of the transducer element used in the microphone of Figure 1, and

Figure 4 is a graphical representation of the frequency response characteristic of the microphone of Figure 1.

The hearing aid microphone shown in plan view in Figure 1 comprises a conductive case 10 in which is supported a piezo-electric transducer 11 constructed in a manner hereinafter to be described in detail. Transducer 11 is supported at each end by blocks 12 and 13 of plasticized cellulose nitrate or other suitable firm but flexible material. Transducer 11 is connected with its output across a resistor 14, which resistor may comprise the grid resistor in the input circuit of a hearing aid amplifier (not shown). One of the output terminals 15 is connected to case 10, and the other output terminal 16 is connected to a lead 17 of resistor 14. Lead 17 extends through an insulating bushing 18 to provide an output lead for connection in an electrical circuit. The other lead 19 extends through case 10 and is soldered thereto. A diaphragm 20, part of which has been cut away to show the internal construction of the microphone, is peripherally supported on a flange of case 10 as by cement or the like, and is secured at its center to a loading pin 21 which is centrally secured to transducer 11 by means of cement or the like.

With reference to Figure 2, transducer 11 comprises a pair of polycrystalline aggregate bodies 22 and 23 which are cemented or otherwise securely fastened together by means of a layer 24 of cement or the like. Bodies 22 and 23 are constructed of a polycrystalline aggregate and have individually been subjected to the reverse alternate polarization process described and claimed in the previously mentioned Adler application. Bodies 22 and 23 thereby possess permanent piezo-electric properties with the direction of the piezo-electric axis substantially opposite in longitudinally adjacent portions in each of the bodies. The direction of the piezo-electric axis in each portion is indicated schematically by the arrows in Figure 2, these arrows being placed adjacent bodies 22 and 23 for the purpose of avoiding confusion in the drawing. Bodies 22 and 23 are so arranged that the direction of the piezo-electric axis in each portion of body 22 is opposite to the direction of the piezo-electric axis in the adjacent portion of body 23. Thus, bodies 22 and 23 form a composite bimorphic element.

The outer surfaces of bodies 22 and 23 are provided with spaced conductive strips or electrodes 25—34 transversely disposed between the longitudinally adjacent portions in which the directions of the piezo-electric axes are substantially opposite. As best illustrated in Figures 1 and 3, a plurality of electrical terminal leads 35—39 are supported between bodies 22 and 23 in parallel relation with respective ones of con-

ductive strips 25—34. Alternate terminal leads 35, 37, and 39 are interconnected by means of a conductor 40 to form one output terminal, and the remaining terminal leads 36 and 38 are interconnected by a second conductor 41 to provide a second output terminal.

With this arrangement, when the composite element is loaded at its center by diaphragm 20 fixed to loading pin 21, those portions of body 22 which are placed in tension are immediately adjacent corresponding portions of body 23 which are placed in compression. Since the direction of the piezo-electric axis in each portion of body 22 is opposite to the direction of the piezo-electric axis in the adjacent portion of body 23, the output voltages generated by bodies 22 and 23 and appearing between output terminals 40 and 41, reinforce each other. For example, when the portion of body 22 between electrodes 26 and 27 is placed in tension, the portion of body 23 between electrodes 31 and 32 is placed in compression. Since the directions of the piezo-electric axes in these two portions are opposite, the electrical output between electrodes 26 and 27 due to the tensile stress on body 22 is of the same polarity as the voltage appearing between electrodes 31 and 32 due to the compressive stress on body 23.

As best seen in Figure 1, bodies 22 and 23 are wider at the center than at the ends. This dimensional relationship is utilized to approach conditions of uniform stress in the transducer when the element is loaded. Thus, bodies 22 and 23, supported at the ends by means of supporting blocks 12 and 13 and loaded in the center by means of loading pin 21, comprise uniform strength beams, and optimum dynamic conditions are obtained.

In accordance with one feature of the present invention, the central conductive strips or electrodes 27 and 32 are connected to case 10 by means of terminal 37 and conductor 40. Because the central point at which loading pin 21 is affixed is thus maintained at the same potential as case 10, diaphragm 20 may be conductively affixed to loading pin 21 to provide effective electrostatic shielding for transducer 11.

The construction of the transducer element is shown in detail in Figure 3. In accordance with the invention, the terminal leads 35—39 are supported between bodies 22 and 23, and adjacent terminal leads are electrically connected to the respective conductive strips on the outer surfaces of the composite element at opposite edges thereof. These electrical connections may conveniently be made by daubs 42—46 of conductive paint bridging the gaps between the ends of the respective terminal leads 35—39 and the respective conductive strips 25—29. With this arrangement, flexure of terminal leads 35—39 which occurs in ordinary handling of the unit is prevented from rupturing the electrical connection between the terminal leads and the electrodes on the outer surfaces of the element, since the terminal leads are firmly supported between the component bodies.

Merely by way of illustration, and in no sense by way of limitation, it may be desirable to describe the process of manufacturing a unit such as that shown in Figure 3. Bodies 22 and 23 may each be constructed of a ceramic composition comprising substantially 98% of barium titanate and substantially 2% of stannic oxide bound by a ceramic binder, as disclosed and claimed in the copending application of Antonio R. Rod-

riguez, Serial No. 65,502, filed December 15, 1948, for "Ceramic Materials," now U. S. Patent 2,533,140 issued December 5, 1950, and assigned to the present assignee. Bodies 22 and 23 may individually be $\frac{5}{8}$ inch long, and the transverse dimensions may be $\frac{5}{16}$ -inch at each end and $\frac{1}{16}$ -inch at the center. The thickness of each of the bodies may be .0075-inch.

The conductive strips on the outer surfaces of the bodies may be formed of silver or other conductive paint applied thereto by means of a silk screen process and subsequently fired to the ceramic surface. In order to avoid difficulties arising from the paint spreading during the silk screen process, the individual strips are made shorter than the width of the bodies. The conductive strips may be equally spaced and may individually have a width of .020-inch.

The bodies 22 and 23 so prepared are then individually subjected to the reverse alternate polarization process described and claimed in the above-mentioned Adler application; briefly, a steady electric field is applied to the bodies, the direction of the field being opposite between adjacent pairs of electrodes. By way of example, an electric field of 20,000 volts per centimeter may be applied for 20 minutes.

After removing the electric field, the bodies are juxtaposed so that the directions of the piezo-electric axes in immediately adjacent portions thereof are everywhere opposite as explained in connection with Figure 2.

Terminal leads 35-39 are interposed between the bodies in parallel relation with the conductive strips, and the bodies are firmly united by cement or the like. Terminal leads 35-39 may be of molybdenum and may individually have a thickness of .001-inch and a width of .010-inch. Daubs 42-46 of conductive paint are applied to connect terminal leads 35-39 to the respective conductive strips on the outer surfaces of the composite element.

In order to provide a pair of output terminals, terminal leads 35, 37, and 39 are connected to conductor 40 which may be a nickel strip, and terminal leads 36 and 38 are connected to another conductor 41 similar to conductor 40.

A unit so formed is characterized by a capacity of about 40 micro-microfarads and an electro-mechanical coupling coefficient of about 25%.

The structure of Figure 3 effectively minimizes the undesirable shunt capacity encountered in similar transducers utilizing electrode patterns in the form of a pair of inter-meshing combs while providing improved mechano-electrical conversion efficiency. This desirable result is due to the fact that the output terminals 40 and 41 are removed from the ends of the conductive strips 25-29 and are separated from the ceramic bodies 22 and 23 by air having a dielectric constant much smaller than that of the polycrystalline aggregate.

Figure 4 is a graphical representation of the frequency response characteristic of a hearing aid microphone constructed in accordance with Figures 1-3. In Figure 4, the microphone voltage output is plotted in decibels as a function of the sound frequency. The ordinates of the curve of Figure 4 are referred to a zero-decibel reference of one volt from a pressure applied at the loading point of one dyne per square centimeter. The response characteristic is quite similar to that obtained with a conventional crystal microphone now used in commercial hearing aids, being characterized by a resonant rise at a fre-

quency of about 3,000 cycles per second and having a useful range from about 200 cycles per second to about 4,000 cycles per second.

Throughout the specification, and in the appended claims, the effect induced by the polarization of a polycrystalline aggregate is termed a "piezo-electric" effect. It is recognized that there exists a controversy over the proper terminology for this effect, and some eminent authorities refer to the effect as an "electrostrictive" one. It is to be clearly understood that, in the sense used in this application, the term "piezo-electric" is to be construed as descriptive of the property of a material of developing electrical voltage in response to mechanical stress.

The present invention provides a novel type of piezo-electric transducer which is inexpensive, rugged, durable, and readily adaptable to mass production techniques. A microphone comprising a transducer constructed in accordance with the invention affords a frequency response characteristic comparable with that obtained with a conventional hearing aid microphone embodying a Rochelle salt crystal, but at a much lower cost.

While a particular embodiment of the present invention has been shown and described, it is apparent that various changes and modifications may be made, and it is therefore contemplated in the appended claims to cover all such changes and modifications as fall within the true spirit and scope of the invention.

I claim:

1. A piezo-electric transducer comprising: a composite bimorphic element including a pair of juxtaposed polycrystalline aggregate bodies and having permanent piezo-electric properties with the direction of the piezo-electric axis different in adjacent portions of each of said bodies; conductive strip terminals disposed on the outer surfaces of said composite element between said adjacent portions; a plurality of terminal leads supported between said bodies for the entire width thereof and individually electrically connected with respective ones of said strip terminals; and a pair of conductors respectively connecting alternate ones of said terminal leads to provide a pair of output terminals.

2. A piezo-electric transducer comprising: a composite bimorphic element including a pair of juxtaposed polycrystalline aggregate bodies and having permanent piezo-electric properties with the direction of the piezo-electric axis different in longitudinally adjacent portions of each of said bodies; spaced conductive strip terminals disposed on the outer surfaces of said composite element between said longitudinally adjacent portions; a plurality of terminal leads supported between said bodies for the entire width thereof in parallel relation with and electrically connected to respective ones of said strip terminals; and a pair of conductors respectively connecting alternate ones of said terminal leads to provide a pair of output terminals.

3. A piezo-electric transducer comprising: a composite bimorphic element including a pair of juxtaposed thin substantially diamond-shaped polycrystalline aggregate bodies and having permanent piezo-electric properties with the direction of the piezo-electric axis substantially opposite in longitudinally adjacent portions of each of said bodies; spaced conductive strip terminals disposed transversely of said axis on the outer surfaces of said composite element between said longitudinally adjacent portions; a plurality of

terminal leads supported between said bodies for the entire width thereof in parallel relation with respective ones of said strip terminals; adjacent ones of said terminal leads being electrically connected to said respective strip terminals at opposite edges of said composite element; and a pair of conductors respectively connecting the free ends of alternate ones of said terminal leads to provide a pair of output terminals.

4. A piezo-electric transducer comprising: a composite bimorphic element including a pair of juxtaposed uniform-strength beams of polycrystalline aggregate having permanent piezo-electric properties with the direction of the piezo-electric axis substantially opposite in longitudinally adjacent portions of each of said beams; equally spaced conductive strip terminals disposed transversely of said axis on the outer surfaces of said composite element between said longitudinally adjacent portions; and a plurality of terminal leads supported between said beams for the entire width thereof in parallel relation with respective ones of said strip terminals, adjacent ones of said terminal leads being electrically connected to said respective strip terminals at opposite edges of said composite element.

5. A microphone for use in hearing aids and the like comprising: a conductive case constituting one output terminal; a piezo-electric transducer supported in said case and comprising a composite bimorphic element including a pair of juxtaposed polycrystalline aggregate bodies having permanent piezo-electric properties with the direction of the piezo-electric axis substantially opposite in longitudinally adjacent portions of each of said bodies, spaced conductive strip terminals disposed transversely of said axis on the outer surfaces of said composite element between said longitudinally adjacent portions, and a plurality of terminal leads supported between said bodies in parallel relation with and individually electrically connected to respective ones of said strip terminals; means connecting alternate ones of said terminal leads to said case thereby electrically connecting alternate ones of said strip terminals to said case; an electrically conductive resilient diaphragm peripherally supported by

5 said case and electrically and mechanically fixed to said element at a point on one of said alternate strip terminals; and means insulated from said case for interconnecting the remainder of said terminal leads to provide a second output terminal.

6. A microphone for use in hearing aids and the like comprising: a case constituting a grounded output terminal; a piezo-electric transducer supported in said case and comprising a composite bimorphic element including a pair of juxtaposed polycrystalline aggregate uniform-strength beams having permanent piezo-electric properties with the direction of the piezo-electric axis substantially opposite in longitudinally adjacent portions of each of said beams, equally spaced conductive strip terminals disposed transversely of said axis on the outer surfaces of said composite element between said longitudinally adjacent portions, and a plurality of terminal leads supported between said beams in parallel relation with and individually electrically connected to respective ones of said strip terminals; means grounding alternate ones of said terminal leads to said case to ground the conductive strip terminals connected to said alternate leads; an electrically conductive resilient diaphragm peripherally supported by said case and electrically and mechanically fixed to said element at a point on one of said grounded strip terminals; and means insulated from said case for interconnecting the remainder of said terminal leads to provide a second output terminal.
